DENTAL CLEANING IMPLEMENT

Harry Bender, Overhill Road, Elmsford, N.Y. 10523

Filed May 17, 1968, Ser. No. 11,985

Term of patent 14 years

Int. Cl. D4—02; D24—99

U.S. Cl. D4—24

Fig. 1

Fig. 2

Fig. 3

Fig. 4

Fig. 5

FIGURE 1 is a view in perspective of a dental cleaning implement showing my new design;

FIGURE 2 is a bottom plan view thereof;

FIGURE 3 is a side elevational view thereof;

FIGURE 4 is an end elevation as seen from the left of FIGURE 3;

FIGURE 5 is an end elevational view as seen from the right of FIGURE 3.

I claim:

The ornamental design for a dental cleaning implement, substantially as shown.
